UNITED STATES PATENT OFFICE.

HENRY B. WEIPER, OF EAU CLAIRE, WISCONSIN.

SEPULCHER-COVER.

1,073,377.

Specification of Letters Patent. Patented Sept. 16, 1913.

Application filed August 17, 1907. Serial No. 389,087.

To all whom it may concern:

Your petitioner, HENRY B. WEIPER, a resident of Eau Claire, Wisconsin, prays that Letters Patent may be granted to him for 5 the Sepulcher-Covers set forth in the annexed specification.

This invention relates to an improvement in sepulchers by which a speedy construction and closing after interment is possible, 10 obviating the necessity of building vaults, which are generally constructed during the life-time of those who desire to escape the underground burying in their final resting place.

15 The object of my invention is to provide in a combined form, a sanitary, economical, and esthetic way to dispose of the dead. A way, in which the underground burying is entirely obviated. The tombstone becomes 20 superfluous and the coffin with its customary rough box can be dispensed with if desired.

From a sanitary standpoint it will satisfy all reasonable demands. Chemicals may be placed in such a sepulcher when hermetically sealed to retard or prevent decomposition of the body, but even without chemical treatment infectious germs can not escape from such a tomb to injure anyone, nor could water percolate through it to dissolve 30 the poisonous ptomaines, (which always develop in decaying bodies) and carry them downward to contaminate springs or wells, as the water can and often does do through the unsanitary earth grave with its wooden 35 rough box and coffin. These wooden articles are also liable to an early decay and let the ground come down upon the body. The grave caves in and with severe rains its external appearance is often destroyed or 40 entirely lost. All this cannot happen with my new sepulcher, which is to be built into the earth, (preferably out of concrete) but so that its walls will also reach a little above ground, where it is to be closed with an 45 everlasting cover, one upon which the elements, such as fire, wind or water, can have no destructive influence, nor the tooth of time, as far as human reason can foresee.

Such a sepulcher cover can be made with 50 concrete, reinforced by metallic embeddings, with very little cost. But where economy is not required can also be made highly ornamental and to carry the emblems of the different orders and creeds, also the sepulchral

inscription and thereby substitute the old 55 fashioned tombstone, forming a monument which cannot tumble over, like tombstones can often be seen to do in nearly every cemetery.

That some people have been buried alive, 60 is only too true. My invention may also prove useful to prevent such a horrible occurrence, as the sepulcher cover can be placed so as to leave an air space for as many days as desired. Wire screening being used to cover the space to prevent the entrance of vermin until permanently closed.

Such a sepulcher as I will now describe with reference to the accompanying drawings, can be constructed quickly after the 70 death of any person, in less time than the body is generally retained at home before interment. The sepulcher cover, of course, would have to be manufactured in advance and kept on hand to close the sepulcher after 75 interment. The sepulcher can also be made in one solid piece similar to the cover, so as to be on hand when needed under adverse condition, for instance in very low places where the water is troublesome, and would 80 interfere with the walling up with cement blocks or plates.

Figure 1 is a view of the sepulcher cover as it will appear in connection with the upper part of the sepulcher when closed, and 85 carrying the inscription. Fig. 2 is a vertical section of the complete sepulcher, showing the cover in cross section, the metallic pipes and wire netting embedded therein. Also the metallic bed-stead which may be 90 used in place of the coffin. Fig. 3 is a view of a horizontal section of the sepulcher cover showing the metallic pipes and wire netting embedded therein. Fig. 4 shows the sepulcher cover partly cemented in on the left 95 hand side, the right side as it appears before the green cement is applied.

Similar numerals are employed to indicate corresponding parts in the different views.

Referring to the drawings numeral 1 designates the sepulcher cover. Its construction is very simple. In a mold of the size and shape desired and deep enough to make the cover about four inches thick, a layer of 105 green cement is applied to fill the mold about half. The metallic reinforcements are then placed thereon, as soon as set

enough to carry them. The mold is then filled with green cement and the top finished in the style desired. Or, the process can be reversed by making the bottom of the mold 5 to shape the top of cover as desired.

Numeral 2 designates the walls of the sepulcher. In Fig. 2 it shows them to be built with concrete blocks. The wire netting extending nearly or quite to the edges 10 of the cover, thoroughly reinforces it and prevents its cracking, while the rods or pipes hereinafter described, greatly stiffen and strengthen the stock cover in its completed form.

15 In Fig. 4 numeral 3 designates the outer raised edge of the sepulcher wall. This raised edge forms, when the cover is placed to close the sepulcher, the space designated by numeral 5. Said space 5 is to be filled 20 with green cement when the sepulcher is to be sealed, as shown by numeral 6 on the left hand side in Fig. 4.

Numeral 7 designates an excavation in the cover, to provide a place for the inscription which the cover is intended to carry. 25 This cavity 7 is to be filled with green cement and the letters impressed therein while in a semisolid condition. Thus, the inscription can be speedily finished when ordered. For finer work a marble plate carrying 30 the inscription can be cemented in said space.

Numeral 8 in Fig. 1 shows how a glass block may be cemented in the cover so that

the interior of the sepulcher may be inspected any time if desired. 35

Numeral 9 designates the metallic pipes embedded. As shown in Fig. 3 and Fig. 4 the said pipes or rods project from the side of the cover, and can be thus used as handles 40 in lifting the cover and in placing it over the sepulcher. These projections may be left straight as at 10 or may be bent over to form loops as at 11. In either case they will be embedded in the concrete when finished 45 as at 6 and become combined handles and anchoring means.

I claim as my invention:

1. A grave vault cover having a window 50 therein, a reinforcing webbing embedded in the material of the cover and extending throughout the same and across the said window for protecting the same as well as protecting the grave vault.

2. A grave vault cover having an inscription marker receiving recess formed therein, and an inspection and light admitting window, a reinforcing webbing embedded in said cover, and extending throughout the same beneath said recess and across said window to 55 for strengthening the cover and protecting the grave vault and window.

In witness whereof I affix my signature in presence of two witnesses.

HENRY B. WEIPER.

In presence of—

HAZEL V. MERRILL,
GEO. L. BLUM.
